UNITED STATES PATENT OFFICE.

LUCIUS T. GIBBS, OF HEMPSTEAD, NEW YORK.

CAR-HEATING SYSTEM.

No. 878,793.

Specification of Letters Patent.

Patented Feb. 11, 1908.

Application filed August 2, 1905. Serial No. 272,295.

To all whom it may concern:

Be it known that I, LUCIUS T. GIBBS, a citizen of the United States, residing at Hempstead, in the county of Nassau, State of New York, have invented certain new and useful Improvements in Car-Heating Systems, of which the following is a specification, reference being had to the drawing accompanying and forming part of the same.

10 My invention relates to heating railway cars, more particularly those propelled by steam, explosive, or other types of motors the exhaust of which is highly heated, and the object of the invention is to provide 15 means for utilizing the heat of the exhaust to heat the car or cars.

A further object of the invention is to provide devices for this purpose which shall be simple in construction and efficient in operation.

In carrying out my invention in its preferred form I arrange below the car and at each end thereof a casing or chamber and provide the same with pipes or conduits open 25 to the air at their outer ends, and at their inner ends in communication with a conduit extending throughout the length of the car and located inside the same. The interior conduit is provided at suitable points with 30 openings for the escape of air, so that the air received by the open ends of the pipes in the forward chamber as the cars travel will be delivered to the interior conduit and from that delivered to the interior of the car.

35 For the purpose of heating the air thus received and delivered, I provide means for discharging the exhaust from the engine into the forward casing, or both, so that the air-receiving pipes therein will be continually 40 bathed in the highly heated gases constituting the exhaust. The result is that the air in passing through the heating pipes abstracts heat therefrom and thus heated issues into the interior of the car. Such an 45 embodiment of the invention is illustrated in the accompanying drawing, in which

Figure 1 is a diagrammatic section view taken longitudinally through the center of a car to which my invention is applied, and 50 Fig. 2 is an under plan view of the same.

The floor or bottom of the car, which may of course be of any type, is indicated by 1. At the ends thereof and below the floor are 55 chambers 2, 3, having outer walls 4, 5, inner walls 6, 7, and intermediate partitions 8, 9,

leaving compartments 10, 11 between the latter and the said inner walls. Extending from the outer walls to the partitions are open-ended pipes 12, of any suitable number and convenient size. Extending lengthwise of the car inside thereof are air conduits 13, 14, provided at suitable places with groups of discharge apertures 15. The air conduits are in communication with the compartments 10, 11, at each end of the car. It 65 will now be evident that when the car is in motion, as for example in the direction of the arrow in Fig. 1, air will be received by the pipes in the forward chamber, in the present instance the chamber 2, and passing into the 70 compartment 10 it will be delivered to the conduits 13, 14, and flowing back through the same will issue into the interior of the car through the apertures 15.

The motor or motors for propelling the 75 car may be located in any convenient place, but in the present case I have shown them on the under side, between the air chambers, as indicated by 16. From the chambers to the motors extend conduits 17, 18, arranged to 80 receive the exhaust from the latter and deliver the same to the interior of the chambers. By this means the air-receiving pipes 12 are surrounded by or immersed in the highly 85 heated gases from the engine, and being thus heated give up their heat to the air passing through them, and it will therefore be seen that heated air is delivered to the interior of the car from the conduits 13, 14. From the chambers the exhaust is discharged into the 90 atmosphere through openings 19, 20.

One of the chief advantages in my invention, besides the matter of economy, is that of ventilation. It will be seen that the heated air is drawn from the outside and 95 supplied in large volume to the inside of the car and distributed along the rows of seats, where most needed. By means of dampers 21, 22, in the inner walls of the chambers 2, 3, the heating and ventilation of the car may 100 easily be regulated. Thus, the farther the forward damper is opened, the greater will be the amount of air escaping therethrough, instead of being deflected up into the conduits 13, 14. In warm weather the forward 105 damper may be placed wide open, thus cutting off the supply of air, while the rear damper is closed, the effect being to draw air from underneath the seats and discharge it outside through the rear chamber. In 110

this case if the ventilators in the top of the car are open, fresh air will enter therethrough, fall to the floor, and be discharged by the ejector action of the rear chamber just described, thus producing a constant circulation through the car, with a constant supply of fresh air. Another advantage resides in the muffler effect of the chambers in muffling the explosions, thus reducing the noise of the 10 engine.

It will also be clear that only one chamber and accessory parts may be used if desired but in such case the car must be turned around for its return travel, in order to make 15 the heating apparatus effective. I prefer, however, to equip both ends of the car alike, as shown, so that either end may be the forward end, as ordinary street cars are usually handled.

20 Having now described the preferred embodiment of my invention, what I claim is:

1. In a car-heating system, the combination of a chamber having air-receiving pipes, a compartment into which said pipes discharge, means for heating the air in its passage through said pipes, means for delivering the air from the said compartment into the interior of the car, and means for permitting more or less of the air to escape from the compartment into the atmosphere, thereby regulating the quantity of air discharged into the car, as set forth.

2. In a car-heating system, the combination of a chamber having air-receiving pipes, means for heating the air in its passage through the said pipes, a compartment receiving air from the said pipes and having an escape aperture for the escape of heated air from the compartment into the atmosphere, 35 means for delivering air from the compartment to the interior of the car, and a damper controlling said escape aperture, whereby more or less of the air in the compartment may be permitted to escape into the atmosphere, as set forth.

3. In a car-heating system, the combination of a chamber having air-receiving pipes

extending rearwardly and open at their forward ends to the atmosphere, means for heating the said pipes whereby the air passing through the same will be heated, a compartment located to the rear of the chamber and receiving the air from the said pipes, the rear wall of said compartment having an aperture for the escape of air into the atmosphere, a conduit for delivering air from the compartment into the interior of the car, and a damper for regulating the escape of air into the atmosphere through the aperture in the rear wall of the compartment, whereby more or less air will escape instead of being delivered into the car, as set forth.

4. In a car-heating system, the combination of a chamber having air-receiving pipes, 60 a compartment into which said pipes dis-

charge, having an aperture for the escape of heated air from the compartment into the atmosphere, means for heating the air in its passage through the said pipes, a conduit for delivering air from the compartment into the interior of the car, a damper for the said escape aperture, and means for operating said damper, whereby more or less of the air may be permitted to escape into the atmosphere, as set forth.

5. In a car-heating system, the combination of a pair of chambers, one at each end of the car, air-receiving pipes extending through the chambers and open toward the adjacent end of the car, whereby one or the other set of pipes will receive air, according to the direction of the car's travel, means for heating the air in its passage through the pipes, compartments receiving air from the respective pipes, said compartments being in communication with the interior of the car and being provided also with openings into the atmosphere, and dampers for said openings, whereby the quantity of air delivered to the car may be regulated by permitting more or less of the air in the compartment to escape into the atmosphere, as set forth.

6. In a car-heating system, the combination of a pair of chambers, one located at each end of the car, pipes in the chambers open toward the adjacent ends of the car, compartments behind the pipes to receive air therefrom and provided with openings into the atmosphere, conduits arranged to receive air from the compartments and deliver the same to the interior of the car, connections from the propelling motor of the car whereby the exhaust of the motor is delivered to the chambers to heat the air-receiving pipes therein, and dampers for the said openings in the compartments, whereby more or less of the air in the compartment receiving air from the pipes may be permitted to escape into the atmosphere and the remainder be delivered into the car, as set forth.

7. In a car-heating system, the combination of a transverse chamber at one end of the car, provided with air-receiving pipes open toward the adjacent end of the car and extending rearwardly through the chamber, a compartment at the rear of the chamber, receiving air from the said pipes and having in its rear wall an aperture for the escape of heated air into the atmosphere, a similar but oppositely arranged chamber and compartment at the other end of the car, a motor for propelling the car, means for delivering the exhaust of the motor to the said chambers, whereby air flowing through the air-receiving pipes will be heated, conduits at the sides of the car connecting the compartments and provided with apertures for the discharge of air into the car, and dampers for the escape apertures in the compartments, as set forth.

8. In a car-heating system, the combina-

tion of a compartment, means for delivering heated air into the compartment, said compartment having an aperture for the escape of air into the atmosphere, means for delivering air from the compartment into the car, and a damper for the said escape aperture, whereby more or less of the air in the com-

partment may be permitted to escape into the atmosphere instead of being delivered into the car, as set forth.
